UNITED STATES PATENT OFFICE.

MIZUHIKO NAKAYAMA AND KEIJIRO ADACHI, OF TOKYO, JAPAN.

UTILIZATION OF WASTES OR SCRAPS OF LEATHER.

1,402,085.

Specification of Letters Patent. Patented Jan. 3, 1922.

Application filed October 1, 1920. Serial No. 413,952.

To all whom it may concern:

Be it known that we, MIZUHIKO NAKAYAMA and KEIJIRO ADACHI, subjects, of Emperor of Japan, residing at, respectively, 5 No. 892, Tozuka-machi, Toyotama-gun, Tokyo-fu, Japan, and No. 2, Nishikuromoncho, Shitaya-ku, Tokyo, Japan, have invented certain new and useful Improvements in Utilization of Wastes or Scraps of Leather, 10 of which the following is a specification.

This invention relates to a utilization of wastes or scraps of leather produced in manufacturing leather goods, wherein the waste or scraps which are cut clean in regular 15 shape and size according to occasion, are sewed together longitudinally so as to form belt-shaped strips, in some cases putting intermediate pieces which are either of inferior leather pieces or of other suitable 20 material, between ordinary leather pieces, making them a little narrower than ordinary ones lengthwise, and interweave these belt-shaped strips together, arranging them in such a manner that the seams 25 or intermediate pieces on each strip may be concealed under the ordinary perfect leather pieces of the other strips which run crosswise with it, thus the present invention has for its object to manufacture the leather 30 goods such as bags, satchels, covers of chairs, footwears, etc., of these waste materials of which exterior appearances are fine enough as if they were made of complete material:

In accompanying drawings:—

35 Fig. 1 is a plan view of a belt-shaped strip made of a number of leather pieces sewn together.

Fig. 2 is a plan view on a belt-shaped strip made by putting intermediate pieces between 40 each ordinary leather piece.

Fig. 3 is a plan view of a belt-shaped strip made by sticking or pasting leather pieces on a long strip of cloth.

Fig. 4 is a plan view showing a number of 45 belt-shaped strips which are already shown in Figs. 1, 2 and 3 interwoven into a broad piece of leather material.

As clearly understood in the drawings the process according to this invention is 50 as follows:—

First the wastes or scraps of leather of similar kinds are cut into the most advantageous shape to facilitate making long strips of them, for instance square or rectangular. These small pieces (1) which are 55 preferably uniform in shape and size are

sewed together longitudinally or pasted on some long strips of cloth (5) so that they form belt-shaped leather strips, sometimes putting between these pieces intermediate 60 pieces which may be of inferior leather or of any other suitable material (3) and narrower than the ordinary leather pieces lengthwise, so as to be concealed under the latter when the longitudinal strips are 65 woven together. Then knit or interweave these belt-shaped strips, using some of them as warps and others as woofs, trying at the same time to conceal the seams or intermediate pieces under the ordinary leather pieces 70 of perfect skin, in some cases replacing either one of warp or woof with one which is made of some other material, thus making the interwoven surface present a fine appearance as if it were made of a number 75 of perfect strips of leather. Next give these woven leather materials desirable sizes, by pressing same with sufficient pressure to elongate them so that the gaps between the leather strips can be filled, and finish them 80 by painting with a solution of celluloid or of other suitable material. In case of using intermediate pieces, they must be made a little smaller lengthwise than the ordinary 85 leather pieces under which they are concealed, leaving a margin (4) for seams so that they are not exposed in the least.

Over the thread, with which the leather pieces are sewn together, some kind of paste must be spread so that the unfastening or 90 untying of the thread is prevented.

Having now described our invention and in what manner it is performed, we hereby declare what we claim is:—

1. A process for utilizing waste leather 95 which consists in reducing the same to pieces of substantially equal size and shape, connecting said pieces end to end to form a plurality of strips, interweaving the said strips one with the other to form a leather fabric, 100 and arranging the points of connection of the pieces of each strip beneath pieces of the other strips to conceal the points of connection.

2. A process for utilizing waste leather 105 which consists in reducing superior portions of the same to pieces of substantially equal size and shape, reducing inferior portions of the same to smaller pieces of substantially the same size and shape, connecting 110 said pieces end to end with an inferior piece between each two superior pieces and form-

ing a plurality of strips, interweaving said strips one with the other to form a leather fabric, and arranging the inferior pieces and the points of connection of each strip beneath superior pieces of the other strips to conceal the inferior pieces and the points of connection.

3. A leather fabric composed of a series of strips interwoven with each other, each

strip consisting of a series of pieces of leather arranged end to end and connected together, and the points of connection of the pieces of each strip being concealed beneath the pieces of the other strips.

In testimony whereof we affix our signatures.

MIZUHIKO NAKAYAMA.
KEIJIRO ADACHI.
